2,200,657

REFRIGERANT COMPRESSOR CONTROL

Burton E. Shaw, Bristol, Ind., assignor to Penn Electric Switch Co., Goshen, Ind., a corporation of Iowa

Application November 3, 1938, Serial No. 238,613

6 Claims. (Cl. 62—4)

An object of my present invention is to provide a control structure particularly adapted for the control of refrigerant systems wherein it is desirable to compensate the control for ambient 5 temperature.

A further object is to provide means to compensate the control for ambient temperature in such fashion that the compensation is effective below a predetermined degree of ambient 10 temperature and ineffective when the ambient temperature is above such predetermined degree.

A further object is to provide a compensator which is responsive to ambient temperature and which is so designed and associated with control operating mechanism that it is ineffective for the purpose of compensation when the ambient temperature is above a predetermined degree; is effective only on the cut-out operation of the control when the ambient temperature is adjacent 20 said predetermined degree, and is effective on both the cut-in and cut-out limits of the control when the ambient temperature recedes to below the predetermined degree, the cut-in and cut-out points thereafter being compensated in proportion 25 to the degree of drop in temperature.

With these and other objects in view, the features of my present invention which I believe to be novel and patentable will be pointed out in the claims appended hereto. For a better 30 understanding of the invention in detail, reference is made to the following description and to the accompanying drawing, in which

Figure 1 is a front elevation of a refrigerant compressor control embodying my invention with 35 the cover removed from the casing, portions of the structure shown in section and the refrigerant system and circuit of the motor thereof being shown diagrammatically;

Figure 2 is a diagrammatic view showing normal 40 operation of the control structure when the ambient temperature is above a predetermined degree;

Figure 3 is a similar diagrammatic view showing the position the parts assume when ambient 45 temperature is adjacent the predetermined degree;

Figure 4 is a similar diagrammatic view showing the position of the parts when ambient 50 temperature is below the predetermined degree, and

Figure 5 is a graphical view showing the operation of the control.

On the accompanying drawing I have used the reference numeral 10 to indicate a control housing. A pivot pin 12 is supported therein by a

bracket 13. A bell crank lever having arms 14 and 15 is pivoted on the pin 12.

A supporting bar 16 has mounted thereon a bracket 17. The bracket 17 carries stationary contacts 18 and 19. Another bracket 20 mounted 5 on the bar 16 supports a pivot pin 21. A switch arm 22 is pivoted thereon and has an armature portion 23. Movable contacts 24 and 25 are carried by the switch arm 22 for coaction with the contacts 18 and 19 respectively. 10

A permanent magnet 25 is mounted on the bar 16 by the bracket 17. Terminals 26 and 27 are electrically connected to the bracket 17 and the switch arm 22. These are included in the circuit of a motor M. 15

The motor M is provided for driving a refrigerant compressor RC. The refrigerant system further includes a condenser C, an evaporator E and high and low sides of the refrigerant line at 28 and 29 respectively. A bulb 11 controls the 20 expansion valve V in the usual manner.

The bell crank lever 14—15 is connected to the switch arm 22 by an extension 30 connected with arm 15 and links 31 and 32. The upper end of the link 32 is pivoted to the switch arm 22. 25

For automatically controlling the bell crank lever I provide a bellows housing 33 and a bellows 34 mounted therein. A stem 35 is connected with the head of the bellows 34 and engageable with arm 14 of the bell crank lever to rotate the 30 lever clockwise upon an increase in pressure against the bias of a range-adjusting spring 35a. The tension of the spring 35a is adjustable by a threaded rod 36 entering a nut 37 mounted in the upper end of the spring 35a. A knob 38 is secured to the rod 36 for rotating it. The bellows housing 33 is connected by a line 39 with the low pressure side 29 of the refrigerant system. 35

In connection with the foregoing described control structure, I provide a novel compensating 40 means which will now be described. A bracket 40 is mounted in the housing 10 and carries a pivot pin 41. A lever 42 is pivoted thereon and is retained in a counterbalanced position by opposing forces. The opposing forces are supplied by 45 a spring 43 tending to rotate the lever 42 counterclockwise and a bellows 44 tending to rotate it clockwise. The bellows 44 is contained in a housing 45 which is responsive to ambient temperature and may contain a charge of ether or 50 the like, whereby an increase in ambient temperature surrounding the housing 45 tends to collapse the bellows 44. A stem 46 extends upwardly from the head of the bellows and coacts with the lever 42. The tension of the spring 43 may be adjusted

by a screw 47. Engagement between the lever 42 and the arm 15 of the bell crank lever occurs at certain times. The engagement is with a set screw 48 carried by the lever 42 so that the position of engagement can be varied as desired. A lock nut 49 is provided to retain the adjustment after once made.

Practical operation

10 Referring to Figure 5, a winter cycle of operation is shown by lines *a* and *b*. This may be the normal operation disregarding the compensating bellows 44. Likewise, a normal summer operation is indicated by the lines *c* and *d*. It 15 will be noted that the winter cycle is shorter than the summer cycle. In certain installations this long summer cycle is satisfactory, but it is desirable to lengthen the winter cycles and also 20 lower the cut-in and cut-out points. The normal cut-in and cut-out points are indicated by the lines *CI* and *CO*.

It is very desirable, from the standpoint of 25 efficient operation, to eliminate sliming of the evaporator coils in the winter time and also to prevent dehydration of the contents of the 30 refrigerated space in the summer time. This is particularly desirable in connection with meat which might be purchased with an eighty per cent water content and the content can reduce 35 to sixty per cent if the air in the refrigerated space is comparatively dry.

40 Sliming in the winter time is caused by an absence of adequate air circulation in a refrigerated space. This results in sliming because there is practically no dehydration taking place, whereas it is desirable to have some dehydration 45 to avoid sliming. Also high temperature moisture from the outside, when the door opens, increases the tendency to sliming. By lowering the cut-in and cut-out points in proportion to the lowering of outside temperature below eighty degrees or thereabouts, the temperature of the refrigerated space is pulled somewhat lower and I have found that this accomplishes the desirable result of eliminating slime.

45 On the other hand, long periods of operation in the summer time result in a lower temperature of the evaporator coil and consequently result in dehydration and low humidity but a good air circulation. This air circulation causes excessive hydration and consequently undesirable shrinkage of the products in the refrigerated space. Accordingly, by setting the control so that the desired operation is secured in the 50 summer time, or above eighty-five degrees or thereabouts, the compensator 44, 45 and 46 can take care of what would be an otherwise undesirable operation when the ambient temperature goes below eighty degrees.

55 In Figures 2, 3 and 4, I have shown the bellows 34 and 44 as P and T respectively indicating a pressure-responsive device and a temperature-responsive device. In the summer time when the ambient temperature exceeds a predetermined degree (such, for example, as 85°), ambient temperature causes the bellows 44 to be compressed to such a point that the set screw 48 is retained spaced from the arm 15 of the bell crank lever during its entire range of movement between cut-in and cut-out positions, as shown in Figures 1 and 2 respectively. This arrangement accordingly secures the desirable results of normal operation of the pressure-responsive controller during the summer time. When ambient temperature is adjacent the predetermined

degree such, for instance, as between 80° and 85°, the bellows 44 is so expanded that the set screw 43 will contact with the arm 15 while the arm moves between an intermediate position and cut-out position, as shown by solid lines in Figure 3. As it moves from intermediate position to cut-in position, however, the arm 15 will leave the set screw. This is shown by the lines *e* and *f* in Figure 5 and a new cut-out point *CO*¹. This obviously will lengthen the cycle of operation somewhat, whereas the normal cycle would be according to the lines *e* and *g*.

10 As the ambient temperature further decreases as, for instance, to a point below 80°, the set screw 43 will contact with the arm 15 continuously as shown in Figure 4. This will effect lowering of both the cut-out and cut-in points as indicated at *CO*² and *CI*¹ in Figure 5. A further reduction in ambient temperature will cause 15 still more lowering of the cut-in and cut-out points as indicated at *CI*² and *CO*³, whereby compensation after the ambient temperature has 20 reduced to below 80° will be in proportion to the ambient temperature.

25 From the foregoing it is obvious that the desirable results of no compensation above a predetermined ambient temperature; compensation for the cut-out point only at adjacent the predetermined ambient temperature, and compensation for both cut-in and cut-out points when 30 ambient temperature is below the predetermined degree, is had. Compensation of this character is made possible by a very simple arrangement of the counterbalanced bellows 44 and spring 43, selected, of course, as to size and tension respectively so that the desired type of compensation 35 is secured for any desired ambient temperature at which the cut-out point only of the control is to be modified and there is to be no modification of both the cut-in and cut-out points when ambient temperature is below the predetermined degree.

40 Any desired amount of compensation can be secured by relative changes in the parts of the compensating mechanism. The charge of gas or liquid in the bellows chamber 45 can be changed in character or volume to secure the desired results, or the change in tension per unit of expansion of the spring 43 may be varied by different sized springs. Another way of accomplishing a 45 different degree of compensation is by changing any one of the leverage points at 41, 46, 43 and 48, or by different combinations of changes of the points with relation to each other.

50 In accordance with the provisions of the patent statutes, I have described the principle of operation of my invention together with one embodiment thereof which may be considered as representative, but I desire to have it understood that the embodiment shown is only illustrative 55 and that the invention may be carried out by other means coming under the scope of my claims.

I claim:

55 1. A refrigerant compressor control comprising a switch mechanism in circuit with a refrigerant compressor motor, means responsive to pressure in the low side of a refrigerant system for normally actuating said control between predetermined cut-in and cut-out positions and means to modify the action of said first means comprising means responding to ambient temperature and coacting with said first means to permit normal operation thereof upon ambient temperature above a predetermined degree affecting said means responsive to temperature; to lower the 70

cut-out pressure thereof upon ambient temperature approaching said predetermined degree and to lower the cut-in and cut-out pressures thereof upon ambient temperature dropping below said predetermined degree.

2. A refrigerant compressor control comprising switch mechanism for a refrigerant compressor motor, means responding to the condition of the refrigerant system for normally actuating said switch mechanism between cut-in and cut-out positions and means responding to ambient temperature and coacting with said first means to permit normal operation thereof upon the ambient temperature rising above a predetermined degree; to lower the cut-out point only thereof upon the ambient temperature decreasing to a point adjacent said predetermined degree and to lower both the cut-in and cut-out points upon the ambient temperature decreasing below said predetermined degree.

3. A control for refrigerant compressors comprising control mechanism, a lever operable through a given range to move said control mechanism between cut-in and cut-out positions, condition-responsive means responding to pressure in the low side of the refrigerant system for moving said lever through said range, a second lever engageable with said first lever, ambient temperature-responsive means and a spring opposing each other and connected with said second lever, to position said second lever spaced from said first lever throughout the range of movement of the first lever upon the temperature-responsive means responding to ambient temperature above a predetermined degree; to engage the second lever with the first lever upon movement of the first lever from an intermediate to a cut-out position when the ambient temperature is adjacent said predetermined degree and to engage the second lever with the first lever continuously throughout the range of movement of the first lever when the ambient temperature is below said predetermined degree.

4. A control for refrigerant compressors comprising control mechanism, a lever operable through a given range to move said control mechanism between opposite cut-in and cut-out positions, condition-responsive means responding to

the refrigerant system for moving said lever through said range, a second lever engageable with said first lever, ambient temperature-responsive means and a spring opposing each other and connected with said second lever, to position 5 said second lever to engage the first lever upon movement of the first lever from an intermediate to one of its opposite positions upon said ambient temperature-responsive means responding to ambient temperature adjacent a predetermined 10 degree, and to respectively space said second lever from said first lever throughout the range of movement of the first lever and engage the second lever with the first lever continuously throughout the range of movement of the first 15 lever when the ambient temperature departs in opposite directions from said predetermined degree.

5. A refrigerant compressor control comprising control mechanism for a refrigerant compressor, means responding to the condition of the refrigerant system for normally actuating said control mechanism between cut-in and cut-out positions and means responding to ambient temperature and coacting with said first means to 20 permit normal operation thereof while the ambient temperature remains in one predetermined range and to modify the operation to cause it to depart from normal operation in proportion to a 25 change in the ambient temperature upon departure of the ambient temperature from said predetermined range.

6. In a refrigerant compressor control, means responsive to pressure in a refrigerant system for normally actuating said control between predetermined cut-in and cut-out positions and means to modify the action of said first means comprising means responding to ambient temperature and coacting with said first means to permit normal operation thereof upon one ambient temperature affecting said means responsive to temperature; to alter the cut-out position thereof upon another ambient temperature affecting said means responsive to temperature and to alter both the cut-in and cut-out positions thereof 45 upon still another ambient temperature affecting said means responsive to temperature.

BURTON E. SHAW.
